UNITED STATES PATENT OFFICE.

EDWARD H. FOX, OF OLYMPIA, WASHINGTON.

FASTENING DEVICE FOR TRUNKS.

SPECIFICATION forming part of Letters Patent No. 679,224, dated July 23, 1901.

Application filed December 14, 1900. Serial No. 39,934. (No model.)

To all whom it may concern:

Be it known that I, EDWARD H. FOX, brigadier-general, National Guard of Washington, a citizen of the United States, residing at 5 Olympia, in the county of Thurston and State of Washington, have invented certain new and useful Improvements in Fastening Devices for Trunks, of which the following is a specification.

10 My present invention pertains to trunk-fasteners or securing devices, the construction and advantages of which will be herein-after set forth, reference being had to the annexed drawings, wherein—

15 Figure 1 is a perspective view of a trunk, showing my invention applied thereto; Fig. 2, a front face view of the strap or band tightening device, together with the lock-carrying plate; Fig. 3, a vertical sectional view; Fig. 4, a side elevation of the shell or casing, partly broken away to illustrate certain features of the invention; and Fig. 5, a face view of a portion of a trunk, showing a modified form of the invention.

20 The object of my present invention is to provide means for securing and maintaining proper and sufficient tension on a strap or band which is passed about the trunk, and also to provide means in conjunction with the 25 trunk-lock which shall when the lock is in engagement with the lid inclose or cover the strap-tension mechanism, so that said mechanism cannot be tampered with or operated and at the same time lock the said mechanism against accidental movement or release.

30 In the drawings I have shown two embodiments of my invention, though of course, as will be seen from the following description, it is susceptible of change in form from the 35 two constructions illustrated.

Referring to the drawings, and more particularly to Figs. 1 to 4, inclusive, A denotes the body of the trunk, and B the lid thereof. To the body of the trunk, and preferably

45 though not necessarily in the position shown there is attached a shell or casing C, which extends in through the front wall of the trunk and is secured thereto by suitable rivets or bolts extending through the flange D of the 50 shell or casing which bears directly against the front face or wall, as is most clearly indicated in Figs. 1 and 3. Within said shell

or casing there is rotatably mounted upon a shaft E a drum F, the drum at one end being provided with a series of ratchet-teeth G, 55 while its opposite end is enlarged, forming a shoulder or collar H. Formed in said shoulder or collar H is a series of openings I, adapted and designed to receive a bar or rod, by which motion is imparted to the drum. The 60 said collar or enlargement is also provided with a transversely-extending opening J, countersunk upon the outer face, as is shown in Fig. 4. The shell or casing is likewise provided with an opening L, which when the 65 parts are brought to proper position will align with the opening J.

The strap or band, formed of any suitable material—such as rope, wire, chain, or the like—has one end passed through the opening J, and if it be wire or rope a knot is formed therein and drawn into the countersunk opening or recess J. The opposite end of the band or strap (denoted by the reference-letter M) has connected to it, by preference, a short link 75 N, which when the strap or band has been passed around the trunk is brought into engagement with a pin carried by the drum.

A dog or detent P is secured to one side of the casing in line with the ratchet G and 80 serves to prevent the ratchet, and consequently the drum, from rotating in one direction.

Assuming that the parts are in the position indicated in Fig. 1—that is to say, the strap 85 or band has been passed around the trunk and the link brought into engagement with the pin—motion is imparted to the drum by a lever or bar inserted into the openings I. As the drum rotates it will of course wind 90 the strap or band about it and place the same under tension. The dog or detent P engaging with the teeth G prevents any retrograde movement of the drum, and consequently whatever tension is placed on the strap or 95 band is maintained.

In order to prevent access being had to the drum, and also to maintain the parts in position against any accidental displacement, I provide a cover or plate adapted and arranged to close over the shell or casing and the contained drum. In the figures above referred to the plate Q is pivotally connected to the lower end of the shell or casing and

carries a lock R, which when the plate or cover Q is swung up into position comes into operative relation with a keeper S, secured to the trunk-lid.

5 As will be seen upon reference to Figs. 2 and 3, the plate Q is cut away or notched at its lower end, as at T, to permit the passage of the strap or band at that point. It is also notched or recessed at its upper end, as at 10 U, to afford passage for the strap or band as it passes from the shell or casing at the upper side thereof. Said plate or cover is provided with an inwardly-projecting lug V, which when the cover or plate is swung up 15 into locking position over the shell or casing will come into contact with the lower arm of the dog or detent P and hold said dog or detent against movement, and consequently against disengagement, from the ratchet-teeth 20 of the drum. From this it will be seen that when the cover or plate Q is brought up into vertical position access to the shell or casing is prevented and the parts locked against further movement, which might be caused by 25 the rough usage to which trunks are usually subjected. It is likewise to be noted that the usual lock for the trunk is present and serves not only as the lock but also as a cover or plate for inclosing the strap-tension 30 mechanism.

Should the strap or band break, a new one can be readily put in place by simply rotating the drum until the opening J comes in alignment with the opening L, formed in the shell or casing, which of course is inside of 35 the wall of the trunk.

In Fig. 5 there is shown a modified form of construction wherein instead of the shell or casing being placed or secured within an opening formed within the wall of the trunk the shell or casing (denoted by C') is secured upon the outer face of the trunk. The cover or plate Q' is hinged to the lower end thereof and is swung up over the drum and into engagement with the lock R', carried by the lid. 45

While I have referred throughout the specification to a "trunk," it is manifest that the strap-tension device and the lock-carrying plate or cover may be applied to any form of 50 box or package, and I do not, therefore, desire to be understood as restricting myself to what is generally known by the word "trunk." The word "trunk" where it appears in the claims is to be read with this understanding. 55 It is also to be understood that the lock proper, which is shown in the drawings as being carried by the plate, may be attached to the lid of the trunk and a suitable engaging device or eye carried by the plate. In 60 other words, the invention is not to be restricted to a construction wherein the lock is carried directly by the plate. So, too, instead of having both ends of the band attached to the drum one end of the band may 65 obviously be attached to the shell or casing.

What I claim as new, and desire to secure by Letters Patent, is—

1. In combination with a trunk and its lid; a strap or band passing about the same; a tightening device for said strap or band; and means for inclosing said tightening device after the trunk is closed and the strap or band is placed under tension. 70

2. In combination with a trunk and its lid; a strap or band passing about the same; a 75 tightening device for said strap, mounted upon the exterior of the trunk; and a lock for securing the lid and inclosing said tightening device.

3. In combination with a trunk, a strap or band tightening device carried thereby; a plate hinged adjacent to said device; and a lock carried by said plate. 80

4. In combination with a trunk; a strap or band tightening device carried thereby; a 85 plate hinged adjacent to said device; a lock for the trunk-lid carried by said plate; and means also carried by the plate arranged to hold the tightening device against action when the trunk is locked. 90

5. In combination with a trunk; a shell or casing mounted in one face thereof; a rotary drum carried by said shell; means for connecting a strap or band to said drum; means for holding said drum in its adjusted position; and a lock-carrying plate hinged to said shell. 95

6. In combination with a trunk; a shell or casing mounted in one face thereof; a rotary drum carried by said shell; means for connecting a strap or band to said drum; ratchet-teeth formed at one end of the drum; a dog or detent engaging said teeth; a lock-carrying plate hinged to said shell; and a lug carried by the plate for holding the dog or detent in operative relation with the teeth of the drum when the plate is swung over the shell. 100

7. In combination with a trunk; a shell or casing mounted in an opening formed in one 105 face thereof; and a rotary drum carried by said casing, said drum having an opening formed therein for the attachment for a strap or band, the casing being likewise provided with an opening in its inwardly-projecting 115 wall in line with the opening in the drum.

8. In combination with a trunk; a shell or casing mounted in an opening therein; and a rotary drum having a collar or enlargement formed at one end thereof with an opening 120 extending therethrough in line with an opening formed in the wall of the shell.

9. In combination with a trunk; a shell or casing mounted in one wall thereof; a drum rotatably mounted in the shell and provided 125 with a series of ratchet-teeth in one end and an enlarged head or collar at the opposite end, said collar having a series of openings formed therein; a pin extending out from the drum; a strap M having one end attached to 130 the pin and the opposite end secured to the drum; means for holding the drum in its adjusted position; and a lock-carrying plate hinged to the lower end of the shell or casing. 135

10. In combination with a trunk and its lid; a strap or band passing about the same; a tightening device for said strap or band, mounted in a chamber normally open when
5 said trunk is closed and the band or strap is under tension; and means for closing said chamber.

In testimony whereof I have signed my name to this specification in the presence of two subscribing witnesses.

EDWARD H. FOX.
